CLAIM

The ornamental design for a pet feeding dish, as shown and described.

DESCRIPTION

FIG. 1 is a perspective view of a pet feeding dish showing my new design;

FIG. 2 is a front elevational view thereof;

FIG. 3 is a rear elevational view thereof;

FIG. 4 is a typical side elevational view thereof, all sides being identical to the side shown in FIG. 4;

FIG. 5 is a top plan view thereof; and,

FIG. 6 is a bottom view thereof.

FIG. 1.

FIG. 3.

FIG. 4.

FIG. 6.
